SAFETY RAZOR

John G. Lawrence, Tampa, Fla.

Application May 20, 1935, Serial No. 22,353

11 Claims.

(Cl. 30—65)

The invention relates to the type of razor in which a short and usually flexible blade is clamped between a bed plate having a serrated or toothed margin projecting beyond the razor blade for protecting the face of the user, and a movable clamping plate or head. In razors of this type the sharp edge of the blade is exceedingly delicate and almost certain to be dulled, to some extent, by contact with any hard or semi-hard substances.

The principal object of the present invention is to provide a blade and holder therefor which will permit the application of the blade to the holder, and its removal therefrom, without danger of having the edge or edges brought in contact with any part of the holder.

Other features of improvement will appear in the following description.

The invention, as to some of its features, may be variously embodied. Two forms of the holder are hereinafter described and illustrated in the accompanying drawings, in which

Fig. 1 is an elevation of one form of the improved razor, an end of the head being in view; Fig. 2 is a sectional view on the line 2—2 of Fig. 1;

Figs. 3 and 4 are sectional details on the lines 3—3 and 4—4, respectively, of Fig. 2;

Fig. 5 is a detail elevation of the head of the razor from the same point of view as Fig. 1, the clamping elements being shown in open position to permit the removal of the blade;

Fig. 6 is an elevation showing the head of the razor;

Fig. 7 is a plan section of the head of the razor taken on the line 7—7 of Fig. 5, a blade being shown as about to be introduced into the head;

Fig. 8 is a view in perspective of the clamping plate and its stem;

Fig. 9 is a view in perspective of the blade removed from the holder;

Fig. 10 is a detail view of the head similar to Fig. 2, showing a modified form of construction; and

Fig. 11 is a detail section on the line 11—11 of Fig. 10.

The blade 15 used with either of the illustrated forms of holder, and capable of use with other forms thereof, is in the form of a thin plate of flexible elastic material, the general shape of which is oblong rectangular. The margins of its longer sides 16, 17, are brought to cutting edges. The blade is centrally longitudinally slotted from one end, as shown at 18, the slot 55 extending somewhat beyond half the length of

the blade and its margins being flanged approximately at right angles to the face of the blade but slightly inclined toward the slot, as shown at 19, 19. Beyond the slot 18, preferably to the farther end of the blade, there is a bowed rib 20, the side walls of which may be continuations of the flanges 19, 19. The slot 18 permits the introduction and removal of the blade longitudinally into and from a suitable holder, the flanges 19, 19, and rib 20 being adapted to engage suitable guides for positioning and facilitating the binding of the blade within the parts of the holder.

The holder comprises a suitable handle bar 21, into one end of which is inserted a tubular shank 22, which is secured in place by a tight fitting pin 23. A longitudinally movable spindle 24, which carries the head of the razor, projects through the shank 22, and is slotted, as shown at 25, to receive the pin 23, and its inner end is reduced in diameter and threaded, as shown at 26, to engage a tubular nut 27, which projects beyond the handle 21—a knurled annulus 28 being fitted upon the outer end of this nut and bearing against the outer end of the handle element 21. The nut 27 is provided near its inner end with an annular shoulder 29, which bears against an inwardly facing complementary shoulder formed in the handle bar, the described construction providing for free turning of the nut but preventing its longitudinal movement.

The head of the holder comprises a clamping plate 30, which may be formed integrally with the spindle 24, as most plainly shown in Fig. 3. This clamping plate is provided with a central longitudinal rib on its inner face, to which the spindle 24 is integrally connected, as shown in Fig. 8. The portion 31 of this rib which extends in one direction from the spindle 24 fits within the slot 18 of the blade 15, and snugly between the flanges 19, 19 securely stabilizing the blade against lateral movement. The portion 32 of this rib at the opposite side of the spindle is of such size and shape that it snugly engages within the rib 20 of the blade when the head is closed to clamp the blade, as shown in Figs. 1, 2, and 3, against a suitable bed.

Preferably, though not necessarily, this bed is composed of two movable plates 33 and 34, mounted on a pivot pin 35, set through the spindle 24 and a pivot lug 36 depending from the rib 31. When the head is open the blade is inserted longitudinally, as indicated in Fig. 7, assuming the position of Fig. 5. The head now being closed by the turning of the nut 27, the 55

bed plates 33, 34, are drawn down against and firmly seated upon the end of the shank 22, as shown in Figs. 1 and 3, the clamping plate 30 binding the blade 15 firmly against their upper faces.

5 When the head is opened by the outward thrust of the spindle 24, the parts are brought to the positions shown in Fig. 5, the bed plates 33, 34, being caused to turn on the pin 35 by the engagement with them of a pair of hooked fingers 31, 38, which extend from the end of the shank 22 into pockets formed in the underfaces of these plates, and engage over shoulders 39, 40, formed therein.

10 15 In the construction shown in Figs. 10 and 11, these hooked fingers are dispensed with, an expanding spring 41 being coiled about the pin 35, its end reacting against the two bed plates to cause them to turn on the pivot pin as the head 20 is opened.

15 The bed plates 33, 34, are provided with a series of teeth 44 along their outer margins, over and upon which the edge portions of the blade 15 lie when the parts are in position for use, as shown 25 in Figs. 3 and 4, space being left between the bed plates and the blade at the bases of the teeth for the entrance of material removed from the face of the user, supporting shoulders at the ends of the plates, however, being provided, as indicated at 45, 46. In order to protect the corners of the blade, as well as the face of the user, from accidental injury, each of the bed plates is provided adjacent its end with an upstanding boss, 30 as shown at 42, 43, against which the corners of the blade engage. These bosses are, of course, of very slight elevation, as they are not intended to project above the exposed face of the blade.

20 The blade is entered into the head longitudinally, as suggested in Fig. 7, its slotted end being in advance. The inner end of the rib 20 reaches the spindle 24 when the blade is fully entered. This spindle being now drawn down into the handle by the turning of the nut 27, the parts 40 of the head are brought together to firmly clamp the blade between the plate 30 and the bed plates 33, 34, and the ribs 31, 32, insure its correct positioning. The blade may be removed by opening the head and turning it approximately vertical, the rib 32 being downward, whereupon the blade will drop by gravity. In these operations there is hardly a possibility of the edges of the blade being brought into contact with any part of the head or other object, and hence these 50 edges are not in danger of injury and are dulled only by their contact with the user's face.

25 The clamping plate and bed plates are held against relative turning movement about the axis of the handle by their pivotal connection, and 60 against such movement together by the pin 23 and by the engagement of the hubs for the pivot pin 35 in a transverse slot in the end of the shank 22, when the head is closed to clamp the blade.

65 I claim as my invention—

1. An oblong razor blade having a longitudinal cutting edge, a longitudinally open slot extending from one end, and spring flanges flanking the slot and inclined inwardly with reference thereto.

70 2. A blade for safety razors, the blade being oblong in form and having an open slot from one end through more than one-half its length and having a bowed rib beyond and in line with the slot, the inner end of the rib constituting an abutment for engaging a suitable stop on a holder and

75 the side walls of the rib being adapted to engage a positioning rib.

3. A blade for safety razors, said blade being oblong in form and having an open slot from one end on its median line through more than one-half its length, and a pair of inwardly inclined flanges at the margin of the slot and having a bowed rib beyond and in line with the slot, substantially as and for the purpose described.

4. In a safety razor, a tubular handle, a longitudinally movable spindle within and projecting beyond the handle, a pair of bed plates pivotally mounted on the spindle and having faces for seating against the end of the handle when in service position, a clamping plate mounted on the end of the spindle and having on its inner face a centrally located longitudinal rib, a blade centrally slotted from one end to receive the rib, and means for moving the spindle longitudinally to clamp the blade between the last-named plate 20 and the bed plates.

5. In a safety razor, a tubular handle, a longitudinally movable spindle within and projecting beyond the handle, a pair of bed plates pivotally mounted on the spindle and having faces for seating against the end of the handle when in service position, a clamping plate mounted on the end of the spindle and having on its inner face a centrally located longitudinal rib, a blade centrally slotted from one end to receive the rib and 30 having a longitudinal bowed portion in line with the slot, and means for moving the spindle longitudinally to clamp the blade between the last-named plate and the bed plates.

6. In a safety razor, a tubular handle, a longitudinally movable spindle projecting from the handle and now rotatable relatively thereto, a clamping plate rigidly mounted on the end of the spindle, a pair of bed plates pivotally attached to the spindle and engageable with the end of the handle as the spindle is drawn thereinto, whereby the clamping plate and bed plates are brought into blade binding relation and means for moving the spindle.

7. In a safety razor, a suitable handle, a longitudinally movable spindle projecting from the handle, a clamping plate rigidly mounted on the end of the spindle, a pair of bed plates pivotally mounted on the spindle and engageable with the end of the handle as the spindle is drawn thereinto, whereby the clamping plate and bed plates are brought into blade binding relation, and means adapted to turn the bed plates on their pivot as the spindle is extended to separate them from the compression plate.

8. In a safety razor, a suitable handle, a longitudinally movable spindle projecting from the handle, a clamping plate rigidly mounted on the end of the spindle, a pair of bed plates pivotally mounted on the spindle and engageable with the end of the handle as the spindle is drawn thereinto, whereby the clamping plate and bed plates are brought into blade binding relation, and means adapted to cause the bed plates to turn on their pivot away from the compression plate as the spindle is extended.

9. In a safety razor, a suitable handle, a longitudinally movable spindle projecting from the handle, a clamping plate rigidly mounted on the end of the spindle, a pair of bed plates pivotally mounted on the spindle and engageable with the end of the handle as the spindle is drawn thereinto, whereby the clamping plate and bed plates are brought into blade binding relation, and a pair of fingers projecting from the handle and

engageable with the bed plates to cause them to swing on their pivot as the spindle is extended.

10. In a safety razor, a suitable handle, a longitudinally movable spindle projecting from the handle, a clamping plate rigidly mounted on the end of the spindle, a pair of bed plates pivotally mounted on the spindle and engageable with the end of the handle as the spindle is drawn thereinto, whereby the clamping plate and bed plates are brought into blade binding relation, and a spring adapted to urge the bed plates to turn on their pivot as the spindle is extended.

11. In a safety razor, in combination, a handle, an extensible spindle projecting from the handle, a blade clamping plate carried by the spindle and having a transversely concave inner surface, a flexible blade adapted to seat against the concave face of the plate, and a pair of bed plates pivotally mounted at the end of the handle and movable about their pivots by the relative movements of the handle and spindle to clamp the blade to the plate. 5
